UNITED STATES PATENT OFFICE.

CHARLES GREER, OF NEW CASTLE, PENNSYLVANIA.

DESIGN FOR A DRINKING-GLASS.

43,500.

Specification for Design.

Patented Feb. 4, 1913.

Application filed October 25, 1912. Serial No. 727,777. Term of patent 14 years.

To all whom it may concern:

Be it known that I, CHARLES GREER, a citizen of the United States, residing at New Castle, in the county of Lawrence and State of Pennsylvania, have invented a new, original, and ornamental Design for a Drinking-Glass, of which the following is a specification, reference being had to the accompanying drawing, forming part hereof, in which the figure is a perspective view showing my new design.

I claim:—

The ornamental design for a drinking-glass, as shown.

CHARLES GREER.
